BENCH SCROLL SAW

Albert J. Dremel, Racine, Wis.

Application December 1, 1953, Serial No. 27,852

Term of patent 14 years

(Cl. D93—3)

Fig. 1.

Fig. 2.

*Fig. 3.**Fig. 4.**Fig. 5.**To all whom it may concern:*

Be it known that I, Albert J. Dremel, a citizen of the United States, residing at Racine, State of Wisconsin, have invented a new, original, and ornamental Design for a Bench Scroll Saw, of which the following is a specification, reference being had to the accompanying drawing, forming a part hereof.

Figure 1 is a side elevational view of the bench scroll saw embodying my new design;

Fig. 2 is a top plan view thereof;

Figure 3 is a side elevational view of the bench scroll saw, looking from the opposite side from Figure 1;

Figure 4 is a front elevational view, and
Figure 5 is a rear elevational view.

I claim:

The ornamental for a bench scroll saw, as shown.
